UNITED STATES PATENT OFFICE.

GEORGE E. RYAN, OF NEW YORK, N. Y.

RAILWAY SAFETY APPARATUS.

No. 850,790.

Specification of Letters Patent.

Patented April 16, 1907.

Application filed September 28, 1906. Serial No. 336,532.

To all whom it may concern:

Be it known that I, GEORGE E. RYAN, a citizen of the United States, and a resident of the city of New York, Laurel Hill, borough 5 of Queens, in the county of Queens and State of New York, have invented a new and Improved Railway Safety Apparatus, of which the following is a full, clear, and exact description.

This invention relates to safety appliances or apparatus, and is intended to be used upon railways to prevent collisions. The arrangement is such that the apparatus will operate to prevent head-on collisions as well 15 as rear-end collisions, and the devices employed are entirely automatic in their operation.

The invention consists in the construction and combination of parts to be more fully 20 described hereinafter and particularly set forth in the claim.

Reference is to be had to the accompanying drawings, forming a part of this specification, in which similar characters of reference 25 indicate corresponding parts in all the figures.

Figure 1 is a diagrammatic view showing a portion of a railway-track in plan and illustrating the manner of applying the invention 30 in practice. Fig. 2 is a side elevation showing a portion of the rail and further illustrating the devices employed. Fig. 3 is a vertical central section through one of the track devices. Fig. 4 is a horizontal section taken 35 through a case of one of the track devices and showing the mechanism therein in plan; and Fig. 5 is a diagrammatic view illustrating the wiring of a contact device, which constitutes a feature of the invention.

Referring more particularly to the parts, 40 11 represent the rails of a railway-track upon which it is supposed that trains move in either direction. In installing my apparatus I provide a plurality of track devices 2, 45 which are arranged in the road-bed at a suitable distance apart. This distance should be sufficient to enable a train to come to a full stop after passing one track device before reaching the next. In this connection 50 it should be understood that the longitudinal distances on the track are much reduced in the drawings, so that the distance between two adjacent track devices may represent a half mile or more.

The track devices 2 are preferably double, 55 as illustrated in Fig. 1—that is, they are con-

structed in two distinct parts or mechanisms. One of these mechanisms co-operates with a train passing in one direction, while the other mechanism co-operates with a train passing in the opposite direction. In Figs. 3 and 4 I have illustrated only one of these mechanisms, while in Fig. 1 I have illustrated the complete or double devices. It may be said at this point, however, that the wiring illustrated in Fig. 1 represents simply the wiring which is employed for trains passing in one direction only—that is, from the right to the left. In this way confusion will be avoided. It should be understood, however, that in practice the same wiring is adopted in connection with the second set of mechanisms, each system of track devices and wiring being an exact duplicate of the other system. As illustrated in Figs. 3 and 4, each track device comprises a case 3, in which there is provided a frame 4, carrying oppositely-disposed coils 5 and 6, which are in axial alinement, as shown. The coil 5 is provided with a core 7, which is connected by means of a link 8 with a cam 9, said cam being rigidly attached to a transverse shaft 10, which is rotatably mounted in the frame 4 and the side of the case, as indicated. This cam 9 is substantially heart-shaped, as shown, the point of the heart being cut away, so as to present a shoulder 11, as indicated in Fig. 3. The cam presents an elevated face 12 and a recess or notch 13. The upper wall of the case is provided with a removable cover or plate 14, which is provided with an opening 15, through which there is guided a trip-pin 16. The lower extremity of this trip-pin carries a roller 17, which rests upon the face of the cam 9, as shown. At one side of the pin 16 a roller 18 is provided, which rests against the face of the pin and operates to reduce the friction in guiding the pin vertically. On one side the cam 9 is provided with a counterweight 19, which tends to rotate the cam toward the left, as illustrated in Fig. 3. Within the coil 6 there is provided a core 20, which is pivotally connected with a link 21. The opposite extremity of this link 21 is attached to a dog 22, which is pivotally mounted at 23 and formed with a nose 24, which is adapted to engage under the shoulder 11, so as to hold the cam 9 in the position shown in Fig. 3. In this connection it should be understood that the weight 19 operates to hold the shoulder 11 against the nose of the dog. On its upper face the nose 24 is provided with an

upwardly-projecting pin 25, which is adapted to engage the edge of the shoulder 11, as indicated. The dog 22 is provided with a laterally-projecting foot 26, under which there is provided a spring 27, and this spring tends to force the nose 24 of the dog toward the cam.

In order to prevent water from passing into the interior of the case, the upper edge of the opening 15 is provided with an upwardly-projecting lip 28, and the pin 16 is provided with a cap or head 29, the under side whereof is provided with a groove 30. When the pin is in its depressed position, this groove 30 receives the lip 28, and the passing of water into the interior of the case at this point is effectually prevented.

When it is desired to use the track devices 2 for controlling electric circuits, the shaft 10 is provided with a rigid contact-arm 31, as illustrated in Fig. 3, and this contact-arm is adapted to engage with contacts 32, so as to close the circuit in any common manner.

It should be understood that the vertical section Fig. 3 is taken looking toward the left in Fig. 1, so that the coils 5 are all disposed at the right of the track in passing from left to right, the coils 6 being disposed oppositely, as indicated. In wiring the apparatus I provide a battery 33, one side whereof is connected with the ground at 34, the opposite side of the battery being connected with a line-wire 35. Just beyond each of the track devices with respect to the direction in which each train passes I provide contact devices 36. From the line-wire 35 conductors 37 lead to the contact devices, respectively, one of these contact devices being illustrated in Fig. 5. It comprises a pair of contact-plates 38 and 39, which are adapted to be brought together by a passing train. For this purpose the contact devices are set close to one of the rails, as indicated in Fig. 1, so as to be engaged by the flange of the car-wheel in a well-understood manner. The conductor 37 is connected with the plate 38, while three conductors 40, 41, and 42 are connected with the plate 39. The conductors 40 pass rearwardly along the track and are connected, respectively, with the coils 5. From each of these coils 5 a conductor 43 leads, and these conductors are grounded by attachment to the rails at the points 44. To the conductor 40 aforesaid the wire 41 is attached, so that the wire 40 is connected by a branch with the plate 39 of the contact device rearwardly on the track. I have indicated the contact devices collectively by the numeral 36. However, the contact device which is in advance of the position of a train located at the arrow in Fig. 1 is indicated specifically by the reference-numeral 36^a, while the contact device next in the rear is indicated specifically by the reference-numeral 36^b. The wire 42 leads from the contact 36^a back through the

coil 6 of the track device which is in the rear of the train, and this coil is connected with the ground through a conductor which is attached to the rail at 45. From the conductor 42 a branch conductor 46 leads adjacent to the coil 6, and this conductor passes through a second contact device 47. Beyond the contact device 47 the conductor 46 is connected with the line 35 at the point 48, as shown. In connection with each of the track devices 2 there is arranged one of these contact devices 47, the same being preferably arranged just in advance of the corresponding track device, so as to be operated by a train just before reaching the track device.

The operation of the system will now be described, and throughout the description the coils 5 will be understood to be setting-coils, their purpose being to set the track devices, while the coils 6 will be understood as releasing-coils, their purpose being to release the track devices.

Assuming that a train is disposed near the position of the arrow shown in Fig. 1 and that it has just passed the right-hand one of the two middle track devices and is moving toward the left—that is, in the direction indicated by the arrow—when the train arrives at the contact device 36^b the plates 38 and 39 thereof are brought together. When this occurs, a circuit is closed from the battery 33 to the line 35 through the conductor 37 to the contact-plate 38. In this way circuits are closed through the wires 40, 41, and 42. The circuit through the conductor 40 passes through the coil 5 of the track device which is just in the rear of the train, energizing this coil in such a way as to set the track device in a manner which will appear more fully hereinafter. From this coil the circuit is closed through the ground at 44 by means of the conductor 43. The circuit closed through the conductor 41 passes through the coil 5 of the track device just in advance of the train, the current passing by the conductor 43, which is connected with this track device, to the rail at 44. In this way the track device in the immediate rear of the train becomes set and the track device in advance of the train becomes set. A circuit is also closed through the conductor 42, which extends to the track device which is not immediately in the rear but next to the rear track device. This conductor 42 closes the circuit through the coil 6 of the track device now referred to, so that this track device becomes released, returning to its normal inoperative position. In this way as the train proceeds beyond the track device 36^b there is maintained a set track device just in advance thereof and a set track device just in the rear thereof. The set track device in advance of the train will be maintained set until the train reaches one of the contact devices 47.

When this contact device is reached, a circuit is closed from the line at the point 48 through the conductor 46 and through the coil 6 to the ground at 45. This coil is the releasing-
5 coil of the track device in advance of the engine, so that the track device will be returned to its normal position. In this way it should be understood that as a train passes along the track the apparatus operates automatically to maintain the track devices in set positions in advance and in the rear of the train, and just before the train reaches the track device in advance thereof the apparatus operates automatically to release this device.
10 It should be understood that some part of the train running on this track is provided with a trip-plate or similar device adapted to be engaged by the track device in order to shut off the power of the locomotive, apply
15 the brakes, or give a signal to the engineer. When the track device is in its set position, as indicated in Fig. 3, the pin 16 is projected upwardly to such a height that it lies within the path of the trip device supposed to be carried by the train. When the track devices are in their released position, the pin 16 becomes depressed, the roller 17 lying substantially in the notch 13 of the cam.
20 If two trains should approach dangerously near to each other passing in the same direction, the train in the rear would strike the track device which is set just in the rear of the train in advance and would have its
25

power shut off or otherwise would have its engineer informed as to the presence of the other train. If two trains should advance going in different directions, one of the trains would engage with the track device which is maintained set in advance of the other train, so that even in this case a collision would be prevented.
30

Having thus described my invention, I claim as new and desire to secure by Letters Patent—

In apparatus of the class described, in combination, a plurality of track devices adapted to be disposed at intervals along the roadway, a plurality of contact devices, circuits connecting said contact devices with said track devices and affording means for setting a track device in advance of the train and a track device in the rear of said train, and affording means for releasing the track devices in succession in the rear of said train, a second set of contact devices and circuits connecting the same with said contact devices and affording means for releasing the contact devices in advance of the train.
45 50 55

In testimony whereof I have signed my name to this specification in the presence of two subscribing witnesses.
